UNITED STATES PATENT OFFICE.

ERD V. CROWELL, OF TULSA, OKLAHOMA.

APPARATUS FOR AND METHOD OF CEMENTING OIL-WELL CASINGS.

Application filed June 15, 1920. Serial No. 389,151.

REISSUED

To all whom it may concern:

Be it known that I, ERD V. CROWELL, a citizen of the United States, and a resident of Tulsa, in the county of Tulsa and State of Oklahoma, have invented certain new and useful Improvements in Apparatus for and Methods of Cementing Oil-Well Casings, of which the following is a specification.

- 10 My invention relates to improvements in well casings, particularly those of the type employed in oil and gas wells, and it consists in the constructions, combinations and arrangements herein described and claimed.
- 15 One of the objects of the invention is to provide a cementing shoe for use in connection with an oil or gas well casing, by means of which a cementing mixture, as for example mud-fluid, can be ejected from the lowest section or "oil string" to fill the space between the "oil string" and well bore and thus seal the formation seat against the seepage of water.

A further object of the invention is to provide a cementing shoe for oil or gas well casings, which offers the distinctive and exclusive advantage of providing means for placing a cementing mixture behind the "oil string" while the well is expelling oil and gas and the casing is resting on its formation seat.

A further object of the invention is to provide means for introducing a cementing mixture into the space between the "oil string" and wall of the hole, without having to first plug the hole beneath the casing, raise the casing or work against the high pressure of the oil and gas.

A further object of the invention is to provide means in oil or gas well constructions, enabling the making of a water-tight seal between the casing and rock formation independently of the casing shoe on the lowest extremity of the "oil string" or the texture of the landing formation on which the shoe rests.

A further and important object of the invention is to provide a valve mechanism forming part of the well casing, through which the mud-fluid is ejected behind the casing.

A further object of the invention is to provide a construction by means of which the cementing material may be introduced around the casing while the latter rests on its formation seat before the oil or gas sand has been opened, the entire casing being employed in carrying out this mode of operation.

Another object of the invention is to adopt a method of carrying out the foregoing objects.

Other objects of my invention will appear in the following specification reference being had to the accompanying drawings, in which:

Figure 1 is a longitudinal section illustrating the improved cementing apparatus wherein the whole casing is employed in discharging the cementing material, and

Figure 2 is a detail section of the same structure.

This application is principally concerned with that form of the invention wherein the entire casing is employed during the operation of discharging the cementing material, another apparatus for the same purpose being disclosed in my Patent #1,432,017, October 17, 1922, which is a division of this application.

In order that the reader might be able to more fully appreciate the purpose of the invention, it is thought well to preface the description of the construction and mode of operation by a brief description of oil well casing operation. Casing, as now used in oil field operations is either iron or steel tubular pipe, the kinds and sizes thereof differing considerably in various fields, all according to the peculiar conditions encountered.

A complete column of pipe or casing as placed in the bore of oil wells, is commonly referred to as the "string" of casing. The fundamental purpose of the oil well casing is that of protection, that is to say, to keep the water and other foreign substances from falling into the shot hole at the bottom and thereby either crowding the oil back from the bore or obstructing the lower end of the bore in such a manner that neither oil nor gas can flow.

- In drilling oil or gas wells, the formations passed through as the depth increases consist of alternating layers of lime-stone, shale, and occasionally a stratum of sand. 5 The shale layers predominate over the lime layers as regards number and thickness, and again, the lime layers predominate over the sand layers in the same manner. Usually the underground water finds its channels 10 of flow in the lime or sand strata, the water flowing through the sand stratum generally above or below a lime stratum.
- As the depth of the hole is increased during the drilling operation, water producing lime or sand strata are encountered, the water thus released by the puncturing of the strata by the drill point, settling in the hole and filling it with water. The drilling operations are thus greatly retarded, due to 20 the cushioning effect the water has on the drilling operation of the tools.

Again, the water released from the lime strata washes down over the shale strata below, causing the shale to cave, slough out 25 and fall down the hole. A loose shale formation may thus cave to such an extent as to even entirely bury the tools. An enormous amount of additional work is required in thereafter excavating the material and 30 recovering the tools.

With this brief survey in mind, the need for the improvement which the invention offers will be understood. The invention relates to a construction by which the sealing 35 of a casing in a bore is performed before the oil or gas stratum has been opened. The "oil string" comprises several casing sections 1^a, which occupy a substantially central position in the well bore B, the casing shoe 2 at 40 the lowermost extremity resting on an annular projection of rock or other material, commonly known as the formation seat S. The bore of the well is ultimately intended to communicate with what is known as the 45 shot hole (not shown), but according to the invention the bore is cemented before such communication is established.

Carried by the casing 1^a is the cementing shoe 3^a which is secured to adjacent sections 50 by couplings 5^a. The cementing shoe 3^a is very much like one of the sections of the well casing. Two or more valves 7^a normally close ports 8^a in the annular enlargement 9^a of the shoe 3^a, each being held in place by rather powerful leaf springs suggested at 10^a and clearly shown in my patent referred to.

A section of tubing 25^a is let down through the casing 1^a until the lower end strikes the 60 bottom of the bore B. This tubing has a belt of perforations 35 out of which fluid flows into the casing 1^a in accordance with the arrow, completely filling the inside of the casing and escaping through the ports

8^a into the space between the casing and the 65 wall of the bore. Any ordinary type of tubing packer is used to secure a tight joint between the tubing 25^a and the casing 1^a, two of such packers 36 being shown, however, only the upper rubber having been 70 expanded into engagement with the casing.

The method of operation may readily be understood from the foregoing description. The casing 1^a is let down into the bore until the shoe engages and rests upon the formation S. The cementing shoe 3^a is introduced in the casing 1^a at the desired location from the bottom, the mud fluid outlet valve 7^a being normally held closed by the leaf 75 springs mentioned. The tubing 25^a with its packer mechanisms 36 is lowered into the casing until it strikes the closed bottom of the bore.

Mud fluid or other cementing material is then introduced into the tubing 25^a whence 85 it escapes at the perforations 35. The casing 1^a fills up to the packers 36 the pressure of subsequently inflowing cement forcing the valves 7^a open so that the bore becomes 90 filled as shown. The injector tubing 25 is withdrawn while the cement inside the casing is yet plastic. The cement inside the casing may be removed by suitable means, but that outside of the casing remains in place.

I claim:

1. Means for sealing a well before opening the bore into a productive stratum, comprising a well casing adapted to rest on the formation seat of the bore, with a plurality of valved ports; and tubing let down in the 100 casing, with packing means for securing a joint therebetween and the casing, having perforations through which sealing material is ejected to fill the casing up to the packing means, and then escape through said ports 105 to fill the surrounding bore.

2. Means for sealing a well before opening the bore into a productive stratum, comprising a well casing adapted to rest on the formation seat of the bore, composed of 110 sections and including a ported cementing shoe; tubing let down in the casing, having openings through which sealing material is ejected into the casing; and valves controlling the port, enabling the material to flow 115 out of the casing into the bore but not back.

3. The method of sealing a well consisting of lowering a casing with an opening into the bore of a well and resting it permanently 120 on the formation seat, inserting a cement injector into the casing until it strikes the bottom of the bore, introducing cement by said injector into the inside of the casing until it reaches and flows through the opening and into the bore, withdrawing the injector while the cement is yet plastic, and preventing the return of the cement from the bore through said opening.

4. The method of sealing a well consisting of lowering a casing with an opening into the bore of a well and resting it permanently on the formation seat, inserting a perforated cement injector into the casing until it too rests on the formation seat, introducing cement into said injector causing

it to flow out of said perforation into the casing thence through the opening and into the bore, withdrawing the injector while the cement is yet plastic, and preventing the return of the cement from the bore through said opening. 10

ERD V. CROWELL.
